UNITED STATES PATENT OFFICE.

WILLIAM ALOYSIUS DUFFY, OF NEWPORT, RHODE ISLAND.

CONDENSER FOR DISTILLING PLANTS.

1,272,925.

Specification of Letters Patent. Patented July 16, 1918.

Application filed August 1, 1917. Serial No. 183,893.

To all whom it may concern:

Be it known that I, WILLIAM A. DUFFY, a citizen of the United States, and a resident of Newport, in the county of Newport and 5 State of Rhode Island, have invented a new and Improved Condenser for Distilling Plants, of which the following is a full, clear, and exact description.

My invention relates to water-distilling 10 plants, and has reference more particularly to condensers for plants suitable for distilling salt water.

An object of the invention is to provide a condenser having a series of removable 15 flasks through which the cooling medium is circulated, so that a flask can be easily removed or replaced, as the case may be, without materially affecting the distilling plant.

Another object of the invention is to provide 20 a condenser having a series of flasks connected in parallel.

With the above and other objects in view, the nature of which will more fully appear as the description proceeds, the invention 25 consists in the novel construction, combination and arrangement of parts as herein fully described, illustrated and claimed.

In the accompanying drawings, forming 30 part of the application, similar characters 30 of reference indicate corresponding parts in all the views.

Figure 1 is a side elevation of a condenser for a distilling plant, a portion of 35 the condenser being broken away to show the details of construction; and

Fig. 2 is a cross section on line 2—2, Fig. 1.

Referring to the drawings, 30 is a conduit leading from a boiler to a condenser or condensers 31. The condenser is preferably in 40 the shape of a cylinder having flattened sides. It accommodates a plurality of flasks 32 disposed side by side transversely of the inlet conduit 30, having a shape similar to 45 that of the housing of the condenser but smaller. One side of the housing has a removable trap 33 large enough to allow the removal of a flask. Each of the flasks has at the top and bottom a tubular portion terminating in a union 34 whereby it may be 50 connected to a valve-controlled tubular ex-

tension 35. All of the tubular extensions are connected to a head 36 above and below the housing of the condenser, the lower half serving as an inlet for salt water which is to 55 be circulated through the flasks and pass through the outlet head 36 above the condenser. All of the valve-controlled tubular extensions pass through a block 37 secured to the condenser housing and in which packing glands 38 are accommodated for each of the extensions so as to prevent leakage therethrough.

The condenser housing has a baffle plate 39 in front of the vapor-inlet conduit 30 disposed to deflect the incoming vapors toward the bottom of the condenser housing where the condensation liquid accumulates. The discharge conduit 40 for the condensed distilled vapors has a downwardly-directed elbow 41 which forms a siphoning outlet from the condenser. The flasks, being shallow with a large surface, are reinforced by stays 42 so as to prevent the spreading or collapsing of said flasks during the circulation 75 of the vapors about them and the salt water through them.

By providing enough valve-controlled extensions for each of the flasks, any of the flasks may be cut out or cut in at any time 80 without materially affecting the process of distillation. The provision of individual flasks permits the removal and substitution of a flask at small expense and with little waste of time in the operation of the distilling plant.

It will be noted that the flasks of the condenser are connected in parallel, that there is no means interconnecting the flasks within the condenser, and, therefore, that any 90 one of the flasks may be removed without in any way interfering with the other flasks.

I claim:

In a plant for distilling salt water, a condenser having a housing, said housing having a vapor inlet at one end thereof and a siphoning condensed-vapor outlet at the other end near the bottom of the housing, a baffle within the housing extending from the top in front of the vapor inlet for deflecting the coming-in vapor toward the bottom of the housing, a series of flasks adapted to be

disposed side by side within the housing between the inlet and outlet, said housing having a trap in one of the sides thereof through which a flask may be entered or removed,
5 valve-controlled tubular extensions at the top and bottom of the housing, means for detachably connecting each of the flasks to one

of the extensions of the top and to one at the bottom, and means associated with said valve-controlled tubular extensions for circulating a cooling medium through said flasks.

WILLIAM ALOYSIUS DUFFY.
